UNITED STATES PATENT OFFICE.

ROBERT S. GILBERT, OF WATERFORD, KENTUCKY.

IMPROVEMENT IN HARVESTERS.

Specification forming part of Letters Patent No. **222,582**, dated December 16, 1879; application filed July 10, 1879.

To all whom it may concern:

Be it known that I, ROBERT S. GILBERT, of Waterford, in the county of Spencer and State of Kentucky, have invented certain new and useful Improvements in Reapers; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

My invention relates to reapers; and it consists in the construction and arrangement of certain mechanical devices, whereby a continuous one-direction motion is imparted to an endless-chain cutter-bar; and it further consists in the construction and adaptation to the endless-chain cutter-bar of an adjusting device, whereby a suitable tension is imparted to said cutter-bar, as will be hereinafter more fully described.

In the drawings, Figure 1 is a top-plan view of my invention with a portion of the cutter-bar frame removed. Fig. 2 is a vertical longitudinal section cut through line *x x* of Fig. 1. Fig. 3 is a vertical transverse section of the cutter-bar and frame cut through line *y y* of Fig. 1. Fig. 4 is a top-plan view of a portion of the endless-chain cutter-bar with a portion of the links removed; and Fig. 5 is a plan view of a modified form of tension mechanism to the cutter-bar, with the top of frame removed.

To the body *A* of the reaper I attach in any well-known manner an axle, *B*, so constructed as to revolve with driving-wheels *C* mounted thereupon. Suitable pawl-and-ratchet devices (not shown) may be attached to the wheels and axle, so that the axle is only operated while the reaper is advancing.

Rigidly attached to the axle *B* is a gear wheel, *D*, which meshes into a pinion, *E*, loosely located upon a shaft, *F*. Sliding upon a feather fixed upon the shaft *F*, and operated by a hand-lever, *H*, is a ratchet-toothed collar, *G*, which is made to engage with a corresponding ratchet-toothed surface constructed upon a collar on the pinion *E*. This device operates in a well-known manner to throw in and out of gear the mechanism through which motion

is imparted to the cutter-bar while the reaper is advancing, and may be used as a substitute also for the pawl-and-ratchet mechanism located near the driving-wheels, heretofore mentioned.

Rigidly attached to the shaft *F* is a crown or bevel-gear wheel, *I*, which meshes into a crown or bevel pinion, *J*, securely mounted upon a supplemental vertically-swinging shaft, *K*. This shaft *K* is journaled at its forward end in a box, *L*, pivoted in a line with the central axis of the shaft *F*, and at or near its rear or lower end in a sleeve, *M*, which forms a part of the carriage *N*. Upon the sleeve *M* is hung the inner shoe, *O*, in such a manner as to relieve the shaft *K* from any downward strain. Mounted upon either the forward end of shaft *K*, or upon a projecting sleeve cast upon the pivoted box *L*, through which the forward end of the shaft *K* passes, is an upwardly-projecting post, *a*. To this post is rigidly attached the forward end of drag-bar *Q*, which detachably passes through the carriage *N*, and is pivoted, in a line with the central axis of the supplemental shaft *K*, to a bracket, *b*, located upon the cutter-bar frame *R*. The carriage *N* operates in guides *S*, and is raised or lowered in a circular plane, its center of action being in a line with the central axis of shaft *F*.

Upon the extreme rear end of shaft *K* is rigidly attached a crown or bevel wheel, *P*, which meshes into a like wheel, *T*, mounted upon the upper end of shaft *e*. This shaft, passing down into the frame *R*, has mounted upon its lower end a driving-pulley, *U*. Around this pulley passes an endless-chain cutter-bar, *V*, which also passes around an adjustable pulley, *W*, located within the outer end of the cutter-bar frame. Proper tension is given to the chain by means of a nut, *d*, and screw-shaft *e*, which feeds the outer pulley outwardly or inwardly, as desired.

In Fig. 1 this screw-tension is shown as operating immediately upon the outer pulley; but in practice I find the method shown in Fig. 5 to be more desirable. In this latter device the nut and screw shaft is located in the inner end of the frame *R*, and when operated carries with it all that portion of the frame upon which is mounted the usual fingers *f* and

the outer pulley, W. In Fig. 1 the nut is made accessible to and is retained in position by a slot, *g*, cut through the upper plate of the frame R.

In Fig. 5 the nut operates against a sliding bumper, *h*, which impinges against a block, *i*, molded upon the inner stationary end of the frame. The inner end of the adjustable portion of the cutter-bar frame is guided while being adjusted by means of keys *p p*, which pass through and ride in slots *q q*, cut in the adjustable portion of the frame R.

A caster-wheel is attached to the outer end of my cutter-bar frame, and, when desirable, to the inner end also, in the usual well-known manner.

Upon each link *r* of the chain V is mounted a knife, *k*, in such a manner and of such construction, that when the links are attached to each other in the form of a chain, the knives form one continuous straight cutting-edge, as shown in Fig. 1.

The distance between the centers of fingers *f* is equal to less than one-half of the length of a link or knife, by means of which proportion each section or knife will have entered the third finger before it has left the first. Each link is also provided with a hook, *l*, as shown in Fig. 4, which clasps around a pin, *m*, in the next contiguous link, by means of which each separate link or knife can be easily removed to be sharpened or replaced.

By providing the knives with a fine saw-cutting edge, they operate with better effect than if smooth.

When traveling upon the road the outer end of the cutter-bar frame is raised in the usual manner by means of lever X, which is provided with a drum, *n*, upon which is wound a lifting-chain, *o*, attached at its lower end to the inner shoe or to the inner end of the cutter-bar frame.

A supplemental brace-bar, Y, (shown in dot-

ted lines, Fig. 1,) secured at its forward end to the body of the reaper, and at its rear end to an eye secured to the cutter-bar frame, may be used when desired to give additional strength to the cutter-bar frame and prevent contortion occasioned by too great a lateral pressure upon sleeve M.

Having thus fully described my invention, what I claim as new, and desire to secure by Letters Patent, is—

1. In combination with the driving mechanism mounted upon body A, the shaft K, drag-bar Q, cutter-bar V, carriage N, and segmental guides S, all operating in the manner and for the purpose specified.

2. In combination with the driving mechanism, as described, shoe O, swinging shaft K, segmental guides S, and carriage N, the sleeve M, constructed to operate as and for the purpose specified.

3. In combination with the driving mechanism of a reaper, the drag-bar Q, pivoted box L, projecting post a, and swinging shaft K, all operating as and for the purposes specified.

4. In combination with an endless-chain cutter-bar and pulley, U, the tension mechanism, as described, when operating upon the cutter-bar frame R, carrying the fingers *f*, and the pulley W, in the manner and for the purpose specified.

5. In combination with the endless-chain cutter-bar V, frame R, pulleys U and W, tension screw-shaft e, nut d, guide-pins p, and slots q, the block i and bumper h, all operating as and for the purposes specified.

In testimony that I claim the foregoing I have hereunto set my hand this 14th day of April, 1879.

R. S. GILBERT.

Witnesses:

S. A. TERRY,
HARRY KING.
